APPARATUS FOR CLEANING HYPODERMIC NEEDLES

Philip M. Casady and Richard R. Casady,
Los Angeles, Calif.

Application July 25, 1949, Serial No. 106,598

18 Claims. (Cl. 134—99)

1

This invention relates to an improved apparatus for simultaneously cleaning a plurality of open-ended tubular elements such as hypodermic needles.

Present methods of medical care and treatment require injection of various fluid solutions beneath the skin of a patient by use of hypodermic needles. These needles are attachable to a nipple for connection to a syringe, tube etc. and include an open-ended tubular element having a sharp end for easy penetration of the skin and a suitable shoulder at the other end of the needle for attachment to a nipple. Each needle is preferably cleaned after each injection is made and before it is re-used again. It is important that cleaning of the needle be effective and complete so that no trace of the fluid solution used in the prior injection remains in the needle when it is used for another injection.

Since hypodermic needles are delicate and the points must be kept sharp, the usual method of cleaning such hypodermic needles is to clean each needle separately by hand. Normally the cleaning operation comprises the flushing of each needle with a plurality of cleaning fluids such as a soap solution, alcohol, ether, and compressed air for quickly drying the needle. Obviously when each needle must be cleaned separately by hand, considerable time is consumed. In some large hospitals, where perhaps several thousand injections are made daily, cleaning of needles used requires full time services of several persons. Such individual cleaning of each hypodermic needle is very costly and expensive and requires maintenance of a large supply of needles.

The primary object of this invention is to design and provide an improved apparatus for cleaning a plurality of needles or open-ended tubular elements quickly, efficiently, simultaneously, and in a minimum of time.

Another object of this invention is to provide a cleaning apparatus for hypodermic needles wherein different cleaning fluids are selectively and sequentially passed through the needles without handling of the needles preparatory to introducing a different cleaning fluid through the needle.

Another object of this invention is to provide a novel cleaning apparatus for hypodermic needles wherein a plurality of needles is carried in spaced relation on a movable rack which may be used not only in connection with the apparatus for cleaning the needles but may also be used for storage of needles awaiting cleaning and cleaned needles.

2

Still another object of this invention is to design and provide a cleaning apparatus for hypodermic needles wherein needles carried in spaced relation on a carrier rack are movable into fluid-tight communication with cleaning fluid discharge ports.

A further object of this invention is to provide a cleaning apparatus for hypodermic needles wherein the cleaning operation may be readily observed.

Generally speaking, this invention contemplates a cleaning apparatus for open-ended tubular elements wherein means for supplying cleaning fluid through one end of such tubular elements, such as a duct, is provided with spaced discharge ports including fluid-sealing seating means and a carrier rack supporting elements to be cleaned in spaced relation is adapted to be moved for bringing the elements into fluid-tight communication with said ports including fluid-sealing seating means. The duct is selectively and sequentially connected to control means for supplying a plurality of different cleaning fluids under pressure for passing said fluid through the duct, the ports and the open-ended elements.

In the drawings:

Fig. 1 is a perspective view of an apparatus embodying this invention.

Fig. 2 is a sectional view taken in a vertical transverse plane passing through the apparatus shown in Fig. 1, adjacent one end.

Fig. 3 is a fragmentary sectional view taken in the plane indicated by the line III—III of Fig. 2.

Fig. 4 is a fragmentary view of the manifold and valve arrangement as viewed from a position beneath the window in the top inclined wall of the housing.

Figs. 5, 6 and 7 are detailed views of a needle-carrying rack used with the apparatus shown in Fig. 1; Fig. 5 being a side elevation of the rack; Fig. 6 being a top view of the rack shown in Fig. 5; and Fig. 7 being a sectional view taken in the plane indicated by line VII—VII of Fig. 5.

Fig. 8 is a fragmentary view of the control valve used in the apparatus shown in Fig. 1, the section being taken in the plane indicated by line VIII—VIII of Fig. 4.

Fig. 9 is a sectional view of the valve shown in Fig. 8, the section being taken in a transverse plane indicated by line IX—IX of Fig. 8.

Fig. 10 is a sectional view of the valve taken in the plane indicated by line X—X of Fig. 8.

Fig. 11 is a sectional view of the valve taken in a plane indicated by line XI—XI of Fig. 8.

3

Fig. 12 is a sectional view taken in the plane indicated by line XII—XIII of Fig. 8.

Fig. 13 is a fragmentary view taken in the plane indicated by line XIII—XIII of Fig. 4.

Fig. 14 is a view of the valve selector disk taken in the plane indicated by line XIV—XIV of Fig. 11.

Fig. 15 is a sectional view taken in a vertical transverse plane passing through the axis of the valve as indicated by the line XV—XV of Fig. 8, 10 and showing the valve in closed position.

Fig. 16 is a fragmentary sectional view taken in a vertical transverse plane as indicated by line XVI—XVI of Fig. 3.

Fig. 17 is a fragmentary sectional view taken in the same plane as Fig. 16, but showing the needle carrier guide means in normally released position.

Fig. 18 is a fragmentary sectional view taken longitudinally of the manifold as indicated by the plane XVIII—XVIII of Fig. 16.

Fig. 19 is a fragmentary sectional view taken longitudinally of the manifold as indicated by line XIX—XIX of Fig. 16.

Figs. 20, 21 and 22 show detailed views of a seal or gasket having a discharge port formed of a resilient yieldable sealing material; Fig. 20 being a front view of said seal; Fig. 21 being a sectional view taken on the plane indicated by line XXI—XXI of Fig. 20, and Fig. 22 being a rear view of the seal shown in Fig. 20.

In general, the apparatus shown in Fig. 1, embodying this invention includes a base 1, a hollow housing 2 mounted on a portion of said base, and a plurality of cleaning fluid supply sources indicated by the receptacles 3, 4 and 5, carried adjacent the housing. If desired a small container of compressed air may be also mounted on the base together with the supply receptacles 3, 4 and 5. Such a compressed air container is not illustrated here because, normally, hospitals, laboratories, and doctors' offices are provided with a central source of compressed air suitably piped to points of use. It is contemplated that in the illustration shown compressed air will be piped to the apparatus as indicated by the compressed air line 6.

The means for supplying fluid, such as 3, 4 and 5 and conduits leading therefrom are operably connected to means for controllably passing the fluid to needles to be cleaned. Supported within the housing is a cleaning fluid conducting manifold generally indicated at 7 for conducting the different cleaning fluids to spaced fluid-conducting elements or discharge ports including fluid-sealing seating means. A needle carrier rack 8 carrying a plurality of needles to be cleaned in spaced relation is movable and positionable within the housing for bringing the needles into proper axial alignment with the discharge ports. Spring-biased means supporting the needle-carrying rack in such alignment with the ports is operable by lever handle 9 for bringing one end of each needle into fluid-tight communication with the margins of the respective discharge port.

A control valve generally indicated at 10 selectively connects the different cleaning fluids with the manifold and is operable to sequentially pass different cleaning fluids through all of the needles for completely cleaning and removing all traces of medicinal solutions which may have been retained within the needle.

Obviously any other type of open-ended tubular element capable of being supported in spaced

4

relation with other elements may be cleaned by apparatus embodying this invention.

The base 1 comprises a rectangular flat member of any suitable material of sufficient area upon which to mount housing 2 and the desired number of cleaning fluid supply receptacles such as 3, 4, and 5. The housing 2 includes front and rear walls 11 and 12 respectively, end walls 13 and 14, and a top wall 15 having a diagonally arranged portion 16 provided with a relatively large rectangular opening 17 for mounting a transparent window glass 18 therein by any suitable means, such as an enlarged grommet 19.

End wall 14 may be provided with an elongated triangularly shaped aperture 20 permitting insertion and removal of the movable needle carrier rack 8 in the housing. The elongated aperture 20 serves to permit needles of various length carried on the rack to be inserted within the housing 20 for cleaning.

The manifold 7 may be supported horizontally and inclined about its axis within the housing adjacent to the upper edge of window 18 by suitably spaced supporting brackets 21 of polygonal shape. A manifold securing screw or bolt 22 (Fig. 16) extends through each bracket 21 for threaded engagement with a back plate 23 of the manifold. Each bracket 21 may be secured in any suitable manner to a mounting plate 24 as by screws 25. The mounting plate is fixedly attached to the rear wall 12 of the housing by a plurality of spaced screws or bolts 26.

The manifold 7 may be of laminated construction and comprises in addition to the back plate 35 an intermediate plate 27 and a front plate 28, said plate being held in assembled relation by spaced top and bottom screw bolts 29 extending through said back plate and intermediate plate for threaded engagement with the front plate 28.

The intermediate plate 27 is provided with a plurality of transversely spaced longitudinally extending ducts 30, 31, 32 and 33 for conducting through said manifold a plurality of different cleaning fluids, each duct affording a passage for flow of a separate cleaning fluid. Between the rear plate 23 and the intermediate duct-carrying plate 27 may be a flat gasket 34 affording a continuous seal throughout the length of the manifold for said ducts.

The detail of the intermediate duct-carrying plate 27 is best seen in Fig. 19, wherein it will be readily apparent that the ducts 30, 31, 32 and 33 are formed in parallel spaced relation by grooving one surface of the plate 27. Each duct terminates in end walls 35 adjacent opposite ends of the plate for providing a continuous peripheral marginal surface sealably engaging the gasket 34. Each duct 30, 31, 32, and 33 is provided with a plurality of longitudinally spaced communicating ports 36, 37, 38, 39 respectively, extending from the bottom surface of the duct through plate 27. The communicating ports 36, 37, 38 and 39 may be equally spaced and transversely aligned each aligned group of ports communicating with a common elongated channel 40 provided in the rear surface of the needle sealing and discharge port defining means generally indicated at 41.

The details of sealing means 41 are shown in Figs. 20, 21 and 22 wherein it will be noted that each sealing means 41 is provided with an oval-shaped wall 42 having the channel 40 formed in its rear surface 43. The rear surface 43 of each sealing means sealably engages the marginal surface areas surrounding a group of communicat-

ing ports on the front surface of intermediate plate 27 for preventing leakage of fluid. The front surface of wall 42 is seated against the rear surface of the front plate 28.

Each sealing means 41 provides a common fluid discharge port 45 for channel 40 defined by a generally cylindrical boss 46 projecting outwardly from wall 42 and accommodated within an aperture 47 in the front plate 28. The boss 46 may be circumferentially undercut as at 48 adjacent the wall 42. When the plates 23, 27 and 28 are secured in assembled relationship, each boss 46 protrudes slightly beyond the outer wall surface of the front plate 28 as best seen in Fig. 17.

The sealing means 41 is preferably made of a resilient yieldable sealing or gasketing material so that when an open-end of a needle to be cleaned is pressed in face-to-face relation against edge margins or edge faces 49 of a discharge port 45, the sealing means 41 will provide fluid-tight communication to one end of the needle. The edge margins 49 are resiliently yieldable for sealing adjustment to irregularities in ends of needles to be cleaned, and constitute fluid-sealing seating means which may readily seal with different end structures of needles of various manufacture. The deformation of the edge margins around the discharge port 45 is best seen in Fig. 16 which illustrates a needle and sealing means in fluid-tight contact.

A separate sealing means 41 is provided for each aligned group of communicating ports 36, 37, 38 and 39, the side edges of walls 42 of the sealing means being in abutment as at 50 (Fig. 18). If desired, the sealing means 41 may be made of a single elongated sheet of sealing material having longitudinally spaced transversely extending grooves or channels such as 40 for connecting the communication ports 36, 37, 38 and 39 with a common discharge port such as 45.

Substantially enclosing the manifold 7 between the brackets 21 may be a spring-biased casing 51 of U-shaped cross-section, said casing being slidably movable transversely along the top and bottom longitudinal edges of the manifold for bringing needles carried on the needle carrier into fluid-tight relationship with the sealing means 41. The casing 51 is provided at its open side with spaced inwardly directed needle carrier guide members 52. The guide members 52 are each provided with a longitudinally extending slot 53 opposed to the slot on the opposite member for slidably and guidably receiving longitudinal marginal edges of the needle carrier rack 8. The guide members 52 may be secured to the U-shaped casing in any suitable manner such as screw bolts 54. The inner ends of the guide members 52 may be joined by a transversely extending end bar 55 (Figs. 3 and 4) provided with a centrally disposed stop 56 for defining the approximate proper position of the needle-carrying rack 8 when positioned on the guide means 52. Adjacent the outer end of the guide members 52 may be a transversely extending bar 57 secured as by screws to the guide members 52 for holding the guide members in proper spaced relationship. The outer extremities of each member 52 may be inwardly tapered as at 58.

Means for moving the casing 51 and bringing the needles carried on said rack into fluid-tight communication with the discharge ports is provided by a pair of longitudinally spaced coil springs 59 and a casing actuator means generally indicated by 60. The springs 59 are posi-

tioned between the rear plate 23 and the U-shaped casing 51 (Figs. 16 and 17) by stud screw bolts 61. Each spring 59 is seated at one end against the rear plate 23 and the other end seated against the inner surface of the rear wall of the U-shaped casing 51, each spring being sleeved over a stud bolt 61.

The actuator means 60 comprises spaced lever arms 62 each having one end engaging the rear surface of the U-shaped casing as at 63 and between its ends pivotally supported from a bracket 21 by means of a suitable pin 64. The opposite end of each lever 62 may be provided with a straight edge 65 lying in a plane parallel to and offset from the axis of the lever and adapted to contact flat, angularly disposed surfaces 66 and 67 formed on a cam 68 attached to a cam operating rod 69 extending beneath the manifold 7. Surface 67 lies in a plane spaced a greater distance from the axis of cam 68 than the plane in which surface 66 lies.

The cam rod 69 may be journaled in lower portions of brackets 21 as at 70 and extends outwardly through end wall 13 for fixed connection with the operating handle 9 disposed perpendicular to the axis of the rod, said handle being provided with a suitable knob 72. The rod 69 is provided with a suitable bearing 73 at its passage through end wall 13.

It will be readily apparent from consideration of Figs. 16 and 17 that when it is desired to insert a needle carrying rack into the housing, handle 9 is turned downwardly as indicated in Fig. 17 for rotating cams 68 so that simultaneous engagement of surfaces 67 with lever arms 62 will rotate the arms in a clockwise direction through a small arc for compressing the springs 59 and slidably moving casing 51 so that the guide members 52 will be in spaced relation with the front plate 28 and free to receive a needle-carrying rack. After the rack has been properly positioned in the guide members turning of the handle 9 toward the rear of the housing will bring cam surface 66 into engagement with the lever 62 and will thus permit the springs 59 to urge the casing rearwardly and bring the guide members into abutment with the front plate 28 and afford fluid-tight connection and contactive association between an end of the needles carried by the rack and the fluid-sealing seating means of the fluid-conducting means extending from the manifold.

In order to properly align needles to be cleaned with the spaced discharge ports 45, the needle carrying rack 8 (Figs. 5, 6 and 7) is provided with a plurality of transversely extending slots 71, said slots being spaced with their axis in identical spaced relationship as the axis of the spaced discharge ports. The rack 8 comprises a flat, elongated bar 74 having attached thereto beneath the lower edge of slots 71 a needle supporting plate 75. The plate 75 may be made of any suitable light weight sheet metal, said plate being bent to afford a downwardly extending securing flange 76 and a longitudinally extending upwardly directed needle-contacting ridge 77 defining with the plate 75 a needle socket-receiving recess. The outer downwardly inclined marginal portion 78 of the sheet metal plate 75 terminates in substantially the same plane as that in which the lower edge of rack 8 lies for supporting the rack when placed on a table and for protectively holding needles in horizontal position out of contact with a table. It will be readily apparent from consideration of Fig. 7 that a hypodermic needle to be cleaned is thus securely positioned on the

needle-carrying rack in a desired axial position by means of ridge 77 and reception of neck 79 of the needle socket within a slot 71. To insure proper alignment of the needle-carrying rack with respect to the spaced discharge ports, rack 8 is provided at opposite ends of the slotted portion with guide openings 80 adapted to receive rack alignment pins 81 carried on the outer plate 28. When the pins 81 are engaged within the openings 80 the axes of the needles on the rack 8 are in proper alignment with the axes of the spaced discharge ports.

Each rack 8 may be provided with an end aperture 82 for permitting easy grasp of the needle-carrying rack in its inoperative position within the housing for withdrawal of the rack with the needles carried thereon.

The different cleaning fluid are supplied to the needles through the manifold and selectively controlled by a multiport valve generally indicated at 10, as best illustrated in Fig. 3. The manifold 7 extends beyond the inner bracket 21 for connection with the control valve 10. As best seen in Fig. 19, the ducts 30, 31, 32 and 33 extend to the end portion of the manifold adjacent the control valve 10, said ducts having intake ports 84, 85, 86, 87 respectively longitudinally spaced from each other. The details of the connection of the control valve with the manifold will be described in detail hereinafter.

The cleaning fluid supply receptacles 3, 4 and 5 may contain different cleaning fluids as for example, receptacle 3 may contain a supply of soap solution; receptacle 4, alcohol; and receptacle 5, ether. Additional cleaning fluids may be supplied in like manner if desired.

Each receptacle 3, 4, and 5 is preferably a transparent or translucent bottle having a cap 88 adapted to engage the top of the bottle for an air-tight connection. Each cap 88 may be provided with a supply inlet cap 89 provided with an air-tight sealed connection with the cap 88. Each cap 88 is provided with a compressed air inlet 90 and a fluid outlet 91 having a tube 92 extending almost to the bottom of the container through which fluid may flow through the outlet 91 and into an outlet tube 93. As illustrated in Fig. 4, the soap receptacle 3 is connected to control valve 10 by a continuous tubing 94 coupled to outlet tube 93 of the soap receptacle by a suitable rubber hose section 95. Likewise the alcohol receptacle 4 is connected to the control valve 10 by tubing 96, and the ether receptacle 5 is connected to the control valve by tubing 97.

As mentioned in the early part of the specification, the apparatus is illustrated as being connected to a central compressed air supply source. The compressed air from the supply source is suitably connected to the control valve 10 by tubing 6. In a manner more particularly described in the operation of the control valve compressed air from the tubing 6 passes through the control valve 10 and into tubing 99 connected to a compressed air header 100 for supplying compressed air to each of the cleaning fluid supply receptacles 3, 4 and 5.

The header is provided with spaced outlets connected by tubes 101, 102 and 103 to couplings 104 joining the tubes with respective compressed air inlets 90 in the cleaning fluid supply receptacles. Thus each of the receptacles is provided with compressed air as permitted by the control valve 10 for producing therewithin an air pressure head for moving the cleaning fluid through the respec-

tive tubings 94, 96 and 97 to the control valve and through the manifold to the needles.

The details of control valve 10 are best shown in the drawings by Figs. 8 to 15, inclusive. The control valve 10 includes a multi-disk type valve having a circular bottom disk 105 and an intermediate member 106 secured to the bottom disk by diametrically spaced screw bolts 107. A suitable gasket 108 may be interposed between the disk and the member 106.

Extending axially through disk 105 and member 106 is a valve shaft 110 for rotatably mounting a circular selector disk 111 on the top surface of member 106. The selector disk 111 may have welded thereto a locking washer 112 having diametrically disposed slots 113 formed therein for reception of ends of a locking pin 114 which extends through the valve shaft 110. The valve shaft extends above selector disk 111 and through inclined wall 16 of the housing for fixed attachment to an actuator knob 115. Beneath the bottom disk 105 the valve shaft is provided with a securing nut 116 affording a seat for one end of a coil spring 117, the other end of which is seated against the bottom disk 105, thus spring-biasing the selector disk tightly against the upper surface of the intermediate member 106. The abutting surfaces of member 106 and selector disk 111 are preferably machine finished.

The bottom disk 105 is provided with a plurality of circumferentially spaced intake ports for connection to the cleaning fluid supply tubing. As illustrated, soap tubing 94 may be connected to valve intake port 118; alcohol supply tubing 96 to valve intake port 119; ether supply tubing 97 to valve intake port 120; and air intake port 121 connected to air tubing 122 communicating with the compressed air header 100. The air supply tubing 6 is connected to an air intake valve port 123 and radially outwardly spaced therefrom the bottom disk 105 may be provided with a valve air outlet 124. The outlet 124 is connected to the air line 99 for supplying air to the header 100.

The intermediate member 106 is provided with a plurality of circumferentially spaced pairs of vertical bores 125 and 126, the inner bores 125 of each pair being connected by a passage 138 to the main air valve inlet 123. Likewise the outer bores 126 of each pair are connected by an outer passage 139 communicating with the air valve outlet 124.

The intermediate member 106 is also provided with circumferentially spaced vertical bores aligned for communication with the valve intake ports 118, 119, 120 and 121 in disk 105. These bores are arranged diametrically opposite the pairs of air bores 125 and 126.

Interposed between the valve 10 and the adjacent end portion of the manifold 7 may be a manifold connector member 127 of generally rectangular shape and provided with a plurality of laterally-spaced vertically-disposed bores 128, 129, 130 and 131 of varying length and each adapted to communicate with a duct in the manifold as 31, 30, 32 and 33, respectively. The upper ends of bores 128, 129, 130 and 131 lie in substantially the same plane for communication with their respective angular bores 132, 133, 134 and 135 formed in the intermediate member 106 and presenting circumferentially spaced openings in the top surface of member 106 spaced radially inwardly from the vertical bores communicating with valve intake ports 118, 119, 120 and 121.

The selector disk 111 has a pair of diametrically opposed inverted U-shaped channels 136

presenting radially spaced aligned openings, one U-shaped channel being adapted for alignment with each cleaning fluid inlet and outlet bores in member 106, for permitting passage of cleaning fluid therethrough while at the same time the other U-shaped channel affords communication between the pair of vertical air bores 125 and 126 for supplying compressed air to the header 100. Thus, for each position of the selector disk, air pressure is supplied to the header and to the fluid supply receptacles for moving fluid through the valve into the manifold and through the needles to be cleaned.

As illustrated, rotation of knob 115 and the connected selector disk 111 through 180° will sequentially supply the several different cleaning fluids to the manifold for passage through the needles carried in the rack 8.

Discharge of the several cleaning solutions from the needles may be received, confined and collected in a relatively deep pan 149, mounted within housing 2. The housing 2 may be provided with a pair of longitudinally extending channel members 141 along the bottom edges of walls 11 and 12 for supporting a shallow V-shaped bottom wall 142 of pan 149. The V-shaped bottom wall 142 may be slightly inclined longitudinally to afford suitable drainage of fluid through a drainage outlet pipe 143, which may be provided with a suitable drain valve 144.

For operation of the control valve to permit selective and sequential flow of cleaning fluid into the manifold, the knob 115 may be provided with an outwardly extending annular flange 140, provided with indicia indicating off-position and selective alignment of the selector disk with the ports in the valve for flow of selected cleaning fluids. It will be apparent that a cleaning cycle is completed by turning knob 115 through 180 degrees.

In operation after the needles to be cleaned have been moved into fluid-tight communication with the spaced discharge ports of the manifold 7, turning of knob 115 will produce selective flow of different cleaning fluids from the supply sources through the valve to the manifold and through the needles. As illustrated, this cleaning cycle preferably includes passage of a small quantity of soap solution through the needles, the soap solution being followed by a small quantity of alcohol and then ether. Air is then blown through the needles for further cleaning and drying the needles.

In detail, after the needles to be cleaned have been properly positioned within the housing, valve knob 115 may be turned clockwise until the indicia 1 is opposite reference point 145. In this position the selector disk 111 is related to the intermediate member 106 as indicated in Fig. 9. One of the U-shaped channels in disk 111 coincides with the compressed air bores 125 and 126 60 for permitting flow of compressed air from the air supply to the air header 100 and thence to the fluid supply receptacles 3, 4 and 5. At the same time, the other diametrically opposed U-shaped channel in the selector disk is registered with the vertical bore in member 106 communicating with the soap supply receptacle 3 and also with the angular bore 132 in member 106.

The influence of the air pressure head in receptacle 3 produces flow of soap solution through the soap tubing 94, the valve 10, the manifold connector member 127 into duct 31. The soap solution flows along duct 31 and is discharged through the several communicating ports 37 in the duct-carrying plate 21 to each channel 40 in

the sealing member 41 and thence out the discharge port 45 into and through the needle. As the valve knob 115 is turned sequentially to indicia 2, 3 and 4, the several other different cleaning fluids separately and independently flow from their supply receptacles through the valve, manifold and discharge ports into and through the needles.

It should be noted that the last cleaning fluid is air which blows out under pressure any traces of other cleaning fluids left in the needles. The amount of time necessary to complete the cleaning cycle is less than one minute. The amount of each cleaning fluid, which is passed through the needles may be selectively determined by the operator; as for example, a large quantity of soap solution may be passed through the needles, a slightly less quantity of alcohol and only a relatively small quantity of ether.

It should be noted that the window in the top wall of the housing permits observation of the cleaning operation so that in the event one of the needles is plugged so that fluid cannot pass therethrough, this needle may be readily identified so that the stoppage may be cleared by hand.

With the apparatus contemplated by this invention, cleaning of the plurality of needles illustrated, would require a minimum of time and in practice, the needles are effectively and efficiently cleaned in less than a minute. While the apparatus illustrated provides for holding twelve needles on a rack, it will be obvious that any greater number of needles may be cleaned at the same time by provision of a longer manifold and a needle-carrying rack having a greater capacity. It is likewise contemplated that a plurality of manifolds may be arranged in parallel relationship for handling a larger number of needles. For small doctors' offices, obviously the apparatus may be modified to clean a fewer number of needles than that illustrated.

It will be readily apparent that the needle-carrier rack facilitates handling of the needles before and after cleaning. The racks may be conveniently available so that as needles are used, upon detachment from the nipple they may be immediately placed in the racks. When the rack is filled the used needles carried on the rack may be easily and quickly cleaned by inserting the rack and needles into the housing for cleaning as above described. After cleaning the rack may be used to hold the needles in a convenient place, ready for sterilization.

The employment of four different types of cleaning fluids as illustrated herein is obviously exemplary only, and other cleaning fluids of different type and a greater or less number of cleaning fluids may be used in connection with this apparatus for properly cleaning the hypodermic needles or any other open-ended tubular elements which require cleaning, the manifold and valve construction being modified accordingly.

While the cleaning of the needles illustrated in this invention is performed by use of fluid pressure for moving the different cleaning fluids through the needles, it is contemplated that the apparatus may be conveniently modified by providing suitable sealing means so that the cleaning fluid may be moved from the supply receptacles through the needles under the influence of a vacuum.

It will be readily apparent to those skilled in the art, that the manipulation of the control valve may be automatic instead of manual, as

11

illustrated. A suitable timing control device may be operatively associated with the valve so that the selector disk is automatically turned at predetermined intervals to permit the desired quantities of different cleaning fluids to pass through the needles.

If desired a pressure regulator may be installed within the housing in air supply line 6 in front of control valve 10 for providing a uniform regulatable fluid pressure for imparting flow to the several cleaning fluids.

The apparatus described above for simultaneously cleaning a plurality of open-ended tubular elements will be readily recognized as one which not only thoroughly, efficiently and completely cleans and flushes said elements but also results in a great saving of time and labor.

All changes or modifications coming within the scope of the appended claims are embraced thereby.

We claim:

1. In an apparatus for cleaning a plurality of hypodermic needles, a combination of: a base; a housing and a plurality of cleaning fluid supply containers mounted on said base; a fluid-conducting manifold supported within the housing and having a plurality of longitudinally extending ducts, each for a different fluid, all of said ducts communicating with longitudinally spaced common discharge ports; a needle-carrier rack removably positioned within the housing and adapted to carry a plurality of spaced needles to be cleaned; a spring-biased, movable casing enclosing said manifold and having guide means for said rack; means on said casing engageable with means on said rack for axially aligning the needles to be cleaned with said ports; manually operable means for causing the spring-biased casing to move with relationship to the manifold for bringing ends of the needles into sealable engagement with margins of said ports; and a control valve for selectively connecting the fluid supply containers with the manifold for successively passing different cleaning fluids through all of the needles, said control valve including means for introducing fluid pressure to the supply containers for causing flow of selected cleaning fluid.

2. In an apparatus for cleaning a plurality of hypodermic needles, a combination of: a base; a housing and a plurality of cleaning fluid supply containers mounted on said base; a fluid-conducting manifold supported within the housing and having a plurality of longitudinally extending ducts, each for a different fluid, all of said ducts communicating with longitudinally spaced common discharge ports; a needle-carrier rack removably positioned within the housing and adapted to carry a plurality of spaced needles to be cleaned; a spring-biased movable casing enclosing said manifold and having guide means for said rack; means on said casing engageable with means on said rack for axially aligning the needles to be cleaned with said ports; manually operable means for causing the spring-biased casing to move with relationship to the manifold for bringing ends of the needles into sealable engagement with margins of said ports; and a control valve for selectively connecting the fluid supply containers with the manifold for successively passing different cleaning fluids through all of the needles.

3. In an apparatus for cleaning a plurality of hypodermic needles, a combination of: a base; a housing and a plurality of cleaning fluid supply

12

containers mounted on said base; a fluid-conducting manifold supported within the housing and having a plurality of longitudinally extending ducts, each for a different fluid, all of said ducts communicating with longitudinally spaced common discharge ports; a needle-carrier rack removably positioned within the housing and adapted to carry a plurality of spaced needles to be cleaned; a spring-biased movable casing enclosing said manifold and having guide means for said rack; manually operable means for causing the spring-biased casing to move with relationship to the manifold for bringing ends of the needles into sealable engagement with margins of said ports; and a control valve for selectively connecting the fluid supply containers with the manifold for successively passing different cleaning fluids through all of the needles.

4. In an apparatus for cleaning hypodermic needles, the combination of: a base; a housing with an elongated aperture in one end wall mounted on the base; a fluid-conducting manifold supported within the housing and having a plurality of ducts, each for different fluid, communicating with spaced common discharge ports; a needle carrier adapted to carry a plurality of needles to be cleaned and to be removably inserted within the housing through said aperture; carrier guide means within the housing for positioning needles on the carrier in axial alignment with respect to said ports; selective operable means for moving the carrier and needles against the manifold for sealably holding the needles in communication with said ports; a plurality of sources of different cleaning fluid; and valve means for selectively and sequentially connecting said different sources with said manifold and ducts.

5. An apparatus of the character described in claim 4, wherein a resilient yieldable material defines each discharge port.

6. An apparatus of the character described in claim 4, wherein the selective operable means includes spring means for tightly pressing an end of each needle against margins of a spaced discharge port.

7. An apparatus of the character described in claim 4, wherein a resilient yieldable material defines each discharge port, and the selective operable means includes spring means for tightly pressing an end of each needle against margins of a spaced discharge port.

8. An apparatus of the character described in claim 4, wherein one of the cleaning fluids is operatively related to the control valve and to sources of other cleaning fluids for moving by fluid pressure the other fluids through the valve, manifold, and needles.

9. In an apparatus for simultaneously cleaning a plurality of open-ended hollow tubular elements, the combination of: a duct for cleaning fluids, said duct being provided with a plurality of spaced discharge ports with their axes lying in a downwardly inclined plane; a movable carrier provided with means for holding tubular open-ended elements in spaced relation in said plane; means operable to move said carrier toward said ports for releasably holding one end of each tubular element on said carrier in pressure-tight sealed relation with a port of said duct; and means for selectively connecting said duct with different sources of cleaning fluid.

10. In an apparatus for simultaneously cleaning a plurality of open-ended hollow tubular elements, the combination of: a duct for cleaning

fluids, said duct being provided with a plurality of downwardly directed spaced discharge ports; a movable carrier provided with means for holding tubular open-ended elements in spaced relation; means operable to move said carrier toward said ports for releasably holding one end of each tubular element on said carrier in fluid-tight abutment with opposed marginal faces of a port of said duct; and control means for selectively passing different cleaning fluids through the duct, ports and elements.

11. An apparatus of the character described in claim 10 provided with a yieldable sealing material defining each discharge port whereby margins of each port sealably contact one end face of a tubular element.

12. An apparatus of the character described in claim 10 wherein alignment means are provided for axially positioning each element with respect to a discharge port.

13. An apparatus of the character described in claim 10 wherein said releasable holding means includes resilient means for pressing an end face of each element against margins of a discharge port.

14. An apparatus of the character described in claim 10 wherein said control means is operatively associated with pressure means for moving selected cleaning fluid through the duct, ports, and elements.

15. In an apparatus for simultaneously cleaning a plurality of open-ended, hollow, tubular elements, the combination of: a housing including a wall having an aperture; manifold means within the housing adapted to conduct a plurality of different cleaning fluids and provided with spaced common ports; a movable carrier for supporting said elements in spaced relation and positionable within said housing through said aperture for bringing said elements into axial alignment with respective ports; means for moving the carrier and elements in said housing for sealably engaging under pressure contact open ends of said elements with margins of respective ports for permitting flow of cleaning fluid from the ports into and through said elements; and control means for selectively passing different cleaning fluids through the ports and the elements.

16. In an apparatus for simultaneously cleaning a plurality of open-ended, hollow, tubular elements, the combination of: a housing; manifold means within the housing adapted to conduct a plurality of different cleaning fluids and provided with spaced common ports; a removable carrier supporting said elements and positionable within said housing for bringing said elements into axial alignment with respective ports; spring-biased means for moving the carrier and end faces of supported elements into abutting pressure engagement with margins of respective ports for flow of cleaning fluid from the ports into and through said elements; and control means for selectively passing different cleaning fluids through the ports and the elements.

17. In apparatus for simultaneously cleaning a plurality of tubular elements open at both ends constructed for unobstructed flow of fluid therethrough, means for passing cleaning fluid through one end of said elements, means at the other end thereof for receiving and confining said fluid, including; a plurality of relatively spaced fluid conducting elements provided with fluid-sealing seating means for contactive association with at least one end of each of said tubular elements to be cleaned, a carrier provided with means for holding said plurality of tubular elements, means for optionally positioning said carrier with the said ends of the tubular elements in and out of contactive association with said sealing means, means for imparting movement to said carrier to effect such optional positioning of the tubular elements, means for supplying cleaning fluid to said fluid passing means, and means for controlling the passage of said cleaning fluid from said fluid supplying means to and through said passing means and elements.
18. In apparatus for simultaneously cleaning a plurality of hypodermic needles open at both ends constructed for unobstructed flow of fluid therethrough, means for passing cleaning fluid through one end of said hypodermic needles, means at the other end thereof for receiving and confining said fluid, including; a plurality of relatively spaced fluid conducting elements provided with fluid-sealing seating means for contactive association with at least one end of each of said hypodermic needles to be cleaned, a carrier provided with means for holding said plurality of hypodermic needles, means for optionally positioning said carrier with the said ends of the hypodermic needles in and out of contactive association with said sealing means, means for imparting movement to said carrier to effect such optional positioning of the hypodermic needles, means for supplying cleaning fluid to said fluid passing means, and means for controlling the passage of said cleaning fluid from said fluid supplying means to and through said hypodermic needles.
